US00D826963S

(12) **United States Design Patent** (10) **Patent No.:** **US D826,963 S**
(45) **Date of Patent:** **** Aug. 28, 2018**

(54) **DISPLAY SCREEN WITH ANIMATED GRAPHICAL USER INTERFACE**

(71) Applicant: **Lucis Technologies Holdings Limited**,
Grand Cayman (KY)

(72) Inventors: **Shan Guan**, Fremont, CA (US);
Xiaolin Shi, Hangzhou (CN)

(73) Assignee: **Lucis Technologies Holdings Limited**,
Grand Cayman (KY)

(**) Term: **15 Years**

(21) Appl. No.: **29/578,178**

(22) Filed: **Sep. 19, 2016**

Related U.S. Application Data

(62) Division of application No. 29/541,560, filed on Oct. 5, 2015.

(30) **Foreign Application Priority Data**

Apr. 3, 2015 (CN) 2015 3 0086763

(51) **LOC (11) Cl.** **14-04**

(57) **CLAIM**

The ornamental design for a display screen with animated graphical user interface, as shown and described.

DESCRIPTION

FIG. 1 is the first image in a sequence of a display screen with animated graphical user interface showing our new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof;

FIG. 10 is the tenth image thereof;

FIG. 11 is the eleventh image thereof;

FIG. 12 is the twelfth image thereof;

FIG. 13 is the thirteenth image thereof;

FIG. 14 is the fourteenth image thereof;

FIG. 15 is the fifteenth image thereof;

FIG. 16 is the sixteenth image thereof;

FIG. 17 is the seventeenth image thereof;

FIG. 18 is the eighteenth image thereof;

FIG. 19 is the nineteenth image thereof; and,

FIG. 20 is the twentieth image thereof.

The broken lines in the drawings depict a display screen and portions of an animated graphical user interface that form no part of the claimed design.

1 Claim, 20 Drawing Sheets
